SEDGWICK N. WIGHT, OF ROCHESTER, NEW YORK, ASSIGNOR TO GENERAL RAILWAY SIGNAL COMPANY, OF ROCHESTER, NEW YORK

TRAIN-DISPATCHING SYSTEM FOR RAILROADS

Application filed May 16, 1927, Serial No. 191,734. Renewed April 9, 1930.

This invention relates to a train dispatching system of the wayside signal indicating type, and more particularly to means for continuously and distinctively indicating when a 5 certain track circuit is occupied by a train and the direction from which said train came, over a line circuit also used for controlling wayside signals.

If it is desired to control a distant signal 10 manually but subject to traffic conditions ahead of such signal, and if in addition to this control it is also desired to indicate when a train is passing such signal, it becomes apparent that the signal can never indicate 15 proceed while a train is passing the same and vice versa a train can not accept and pass such signal unless the signal is indicating proceed when it is accepted; and for this reason a line circuit for controlling the signal is only 20 useful for signal control purposes while there is no train passing such signal and further there is never occasion for indicating the passage 25 of a train except when such signal is held at stop by such passing train. Further, it is often extremely important for a train dispatcher who has control over the signal mentioned to know whether the passing train is 30 moving in one direction or the other.

With the foregoing and other important 35 considerations in mind, it is proposed in accordance with the present invention to employ a control relay, which may be a neutral relay or a polar relay depending upon the number of signals to be controlled, to control this control relay over a line circuit from the dispatcher's office, and to provide suitable 40 means for continuously opening this line circuit so long as there is a train passing the signal in question moving in one direction, and to intermittently open said line circuit if there is a train passing the signal moving in the opposite direction.

More specifically it is proposed to employ a 45 polar control relay which is controlled by suitable current preferably direct current, and which if energized in one direction will permit clearing of one signal and if energized in the opposite direction will permit clearing of another signal, to provide a supplemental 50 relay which is directly controlled by a track

circuit and is de-energized if the track circuit is occupied by a train moving in one direction but which supplemental relay has another energizing circuit including a back contact of the control relay whereby this supplemental 55 relay is intermittently energized and in turn intermittently breaks said line circuit.

Other objects, purposes and characteristic 60 features of the invention will appear as the description thereof progresses.

In describing the invention in detail, reference will be made to the accompanying 65 drawings in which:—

Fig. 1 conventionally shows a portion of a railway system having a train dispatching 70 system of the wayside signal indicating type superimposed thereon, and including an arrangement for indicating the position and direction of movement of trains embodying the present invention; and

Fig. 2 illustrates a modified form of the 75 invention in which certain relays perform additional functions and for this reason less relays are required.

Description of Fig. 1.—Referring to Fig. 1 of the drawings, wherein a portion of a train dispatching system such as described in detail in my prior application Ser. No. 120,423 filed July 3, 1926, has been shown, a portion of the main track and track switch, and the signals associated therewith of one passing siding only, has been illustrated. This track switch at one end of the passing siding has been designated TS and the starting signals for the main track and siding have been 80 designated 2 and 2D respectively and the entering signal has been designated 1 and the take-siding signal has been designated 1D. Although the track switch TS may be controlled by a suitable power operated 85 switch machine through the medium of the control relay hereinafter described, and as more particularly described in my prior application above mentioned, such a switch machine has not been illustrated, a switch box 90 contact 5 having been shown for the purpose of controlling the associated signals in accordance with the position of the track switch TS. The track switch TS is provided with the usual fouling or detector track circuit 95 100

including a detector track relay 2DT conventionally shown by a dotted line and by a track battery conventionally illustrated.

Although the invention is applicable to double track railways in which trains move over a track in one direction only and is applicable to a portion of a complicated interlocking system, the invention has for convenience only been shown applied to a single track railway signaling system of the absolute-permissive-block type, of which the home relays 1H and 2H and the usual absolute-permissive-block directional stick relay 2S have been shown.

At each end of each passing siding, or at any other location where the invention is to be applied, there is provided a control relay Z which may be energized from a distant dispatcher's office or tower.

Operation.—It is believed that the invention can be most readily understood by considering the operation of the system. In order to do this let us assume that there is a train on the main track of the passing siding facing in an easterly direction, that is, a train moving from left to right, and that the operator in the dispatcher's office DO wishes to allow this train to proceed into the single-track section and in order to do so he must clear the signal 2. This may be done by energizing the control relay Z toward the right in response to movement of the control lever L in a clockwise direction, whereby the following circuit is completed:—beginning at the positive terminal of a suitable source of energy such as a battery 10, a contact of the control lever L, winding of the line relay LR also located in the tower DO, line wire 11, front contact 12 of the signal relay OS, wire 13, winding of the polar neutral control relay Z, wires 14 and 15, to the common return wire C, which through wires 16 and 17 is connected to the neutral point of the battery 10. With this circuit completed, the polar contacts of the relay Z will assume the position in which they have been shown and the neutral contacts will assume the attracted position, in which the following circuit for clearing the signal 2 is completed: beginning at the terminal B, neutral contact 20 of the control relay Z, polar contact 21 of this relay, wire 22, switch box contact 5 closed when the track switch TS is in its normal position, wire 23, signal control mechanism of the signal 2 (not specifically shown), wire 24, front contact 25 of the home relay 2H to the common return wire C connected to the other terminal of said source of energy. It is thus noted that with the home relay 2H energized manifesting favorable traffic conditions ahead, with the single track section ahead not occupied by a westbound train, and with the track switch TS in its normal position, the signal 2 will assume the clear position. Although the starting and entering

signals shown are in practice three-position signals, and have been conventionally illustrated as such, the circuit for positioning these signals in the caution position have not been shown. Also it is to be understood that three-position light signals may be employed instead of semaphore signals, all in a manner as described in detail in my prior application above mentioned.

The dispatcher now having cleared the signal 2 in response to movement of his lever to the right hand position and also having energized the line relay LR located in the dispatcher's office, let us now consider the movement of the train standing on the main track of the passing siding which in response to clearing of the signal 2 will move into the single track section. As soon as this train treads upon the detector track circuit containing track relay 2DT, this track relay is de-energized thereby causing the signal 2 to assume the stop position, because the energizing circuit of the home relay 2H includes the contact 27 of the detector track relay 2DT, and therefore the home relay 2H is de-energized and in turn the signal 2 is caused to assume the stop position. During the initial movement of the signal blade of signal 2 from its clear or caution toward its stop position and with the detector track relay 2DT de-energized, the following pick-up circuit for the usual APB directional stick relay 2S is completed:—beginning at the terminal B of a suitable battery, back contact 27 of the detector track relay 2DT, wire 28, contact 29 operated by the signal 2 and closed when the signal assumes the clear or caution position, wires 30 and 31, winding of the stick relay 2S to the common return wire C connected to the other terminal of said battery. In this connection it should be noted that a similar pick-up circuit would have been completed through contact 29D had the train moved off of the siding. Although this pick-up circuit for the usual stick relay 2S is only completed for a short time while the signal 2 is moving from the clear or caution position, a stick circuit for maintaining this relay 2S energized is completed, which may be traced as follows:—beginning at the terminal B of said battery, back contact 33 of the home relay 2H, wire 34, front contact 35 of the stick relay 2S, wires 36 and 31, winding of the relay 2S, to the common return wire C. It thus appears that the stick relay 2S will remain energized so long as the home relay 2H remains de-energized, or in other words, the relay 2S is picked up when a train moves from left to right over the detector track circuit containing relay 2DT and remains energized at least as long as this detector track circuit remains occupied. In accordance with the present invention this stick relay 2S in conjunction with the detector track relay 2DT is used for indicating when there is a train moving from left

to right over the detector track circuit containing relay 2DT.

Let us now consider the effect, if any, the entrance of the east bound train in question upon the detector track circuit has upon the line relay LR located in the dispatcher's office DO. It should be noted that the supplemental relay WP is normally energized through the front contact 40 of the detector track relay 2DT, and that the signal relay OS is normally energized through the front contact 46 of the supplemental relay WP. Bearing in mind that the stick relay 2S is now stuck up and that the detector track relay 2DT is now down by reason of an east bound train moving over the detector track circuit containing this relay 2DT, with the contact 40 of the track relay 2DT down, the supplemental relay WP is de-energized and in turn de-energizes the signal relay OS; but since both of these relays WP and OS are preferably slow acting as they have been conventionally shown, a certain amount of time (say one second) elapses before the signal relay OS assumes its de-energized position. When this occurs a supplemental energizing circuit for the supplemental relay WP is completed which may be traced as follows:—beginning at the terminal B of a suitable battery, front contact 41 of the stick relay 2S, wire 42, back contact 43 of the relay OS, wires 44 and 45, winding of the relay WP to the common return wire C connected to the other terminal of said battery. The supplemental relay WP is of course energized in response to the completion of the circuit just traced and after a short interval of time, it will have caused the signal relay OS to be energized, which energization of relay OS in turn again breaks this supplemental energizing circuit. In other words, an oscillating system has been set up which causes the relays WP and OS to be alternately energized and de-energized.

For various reasons, some of which have been mentioned, in my prior application above mentioned, it is desired to maintain the control relay Z energized in spite of opening of the line circuit if this control relay assumed its energized position at the time the line circuit was opened at the control relay end thereof, and for this reason provision has been made for energizing the control relay Z through a stick circuit when the line circuit is opened due to dropping of the signal relay OS. In response to de-energization of the signal relay OS due to dropping of the detector track relay 2DT, the control relay Z is stuck up through the following circuit:—beginning at the positive terminal of the battery 50, polar contact 51 of the control relay Z, wire 52, neutral contact 53 of the control relay Z, wire 54, back contact 12 of the signal relay OS, wire 13, winding of the control relay Z, wires 14 and 55, back contact 56 of the

signal relay OS, wire 57 to the neutral point of the battery 50. It is desired to point out here that the back contact 56 has been provided to normally disconnect the battery 50 from the common wire C, and that this contact 56 may, if desired, be omitted. It should be noted that the polarity of the current applied by the battery 50 is the same as that originally used for picking up the control relay Z derived from the battery 10 in the dispatcher's office, so that the control relay Z will remain stuck up in the same position as that to which it was originally energized.

With the relays WP and OS oscillating in a manner as heretofore described, the line circuit including the line wire 11 is intermittently broken, and for this reason the line relay LR located in tower DO is intermittently energized. This line relay LR through its back contact 60 intermittently energizes the indicating lamp I located on the miniature track lay-out in the dispatcher's office, and thereby indicates to the dispatcher that there is a train moving from left to right over the detector track circuit at the right hand end of the siding in question.

Let us now assume that there is a westbound train moving in the single track section of Fig. 1 and that the dispatcher wishes this train to take the main track. In this connection it should be remembered that the home relay 2H under the conditions assumed is de-energized, because the westbound train in the single track section has caused the eastbound tumble down circuit to be opened and the home relay to be de-energized in the usual way. In order for the dispatcher to clear the signal 1 he will move the lever L in a clockwise direction and thereby cause an energizing circuit for the control relay Z as heretofore traced to be completed, which will again cause this relay Z to assume its right-hand energized position, in which the following circuit for the signal 1 is completed:—beginning at the terminal B, neutral contact 20 of the control relay Z, polar contact 21 of this same relay, wire 22, switch box contact 5 of the track switch TS, wire 61, signal mechanism of the signal 1, wires 62 and 63, front contact 64 of the home relay 1H, wire 65, to the normal return wire C connected to the other terminal of said battery. The completion of this circuit will permit the signal 1 to assume its clear indicating condition. It may be pointed out here that any suitable means, such for instance as shown in my prior application, may be used for selecting between the signals 1 and 2 when the control relay Z is energized to the right, and for convenience no specific means for accomplishing this result has been illustrated in the drawings.

Let us assume that the westbound train in the single track section continues its move-

ment into the main track of the passing siding in response to clearing of the signal 1. When this train enters upon the detector track circuit containing track relay 2DT, bearing in mind that the stick relay 2S is now de-energized, the supplemental relay WP is de-energized and in turn the signal relay OS is de-energized. These relays WP and OS will remain in their de-energized condition so long as the detector track relay 2DT is deenergized, because the supplemental energizing circuit for the relay WP heretofore mentioned is now open at the front contact 41 of the stick relay 2S. In other words, a westbound train will cause the line circuit and in turn the line relay LR in the dispatcher's office to remain de-energized so long as this train occupies the detector track circuit containing relay 2DT, and therefore the indicating lamp I is continuously energized so long as there is a westbound train on the detector track circuit of which traffic conditions are indicated by this signal lamp I.

In the same manner as already described in connection with signals 1 and 2, the take-siding and dwarf signals 1D and 2D may be cleared when the track switch TS assumes the take-siding position. If the track switch TS is not operated by a switch machine, as proposed in my prior application above mentioned, the switch box contacts 5 will be omitted in so far as they control the dwarf signal 2D and the take-siding signal 1D, in which event the train crew in response to clearing of one or the other of these signals 1D and 2D will operate the track switch TS through the medium of the usual switch stand (not shown). It is desired to be understood that the arrangement shown in Fig. 1 in so far as the signal system as a whole is concerned, is conventional and that reference may be had to the prior application for a more complete description as to the control of the three-position signals and the track switches in accordance with the wishes of the train dispatcher, and further that the invention may be applied to a track lay out not employing signals of the absolute-permissive-block type all without departing from the invention shown and described in connection with Fig. 1.

Description of Fig. 2.—In Fig. 2 has been shown a modified form of the present invention in which the supplemental relay WP is entirely omitted, and in which the control relay Z is not stuck up during the time of occupancy of the detector track circuit as was the case in the arrangement shown in Fig. 1. For simplicity the control for the signals 1, 2, 1D and 2D, as well as the home relays 1H and 2H controlling the same, have been omitted, and in like manner the control circuits for the stick relay 2S have been omitted.

Operation of Fig. 2.—It is believed sufficient to point out how the line circuit including the line wire 11¹ in Fig. 2 is caused

to be continuously open when the detector track circuit containing track relay 2DT is occupied while the stick relay 2S is de-energized, and how this line circuit is intermittently broken if the detector track circuit in question is occupied while the stick relay 2S is energized. Let us first assume that there is a westbound train moving over the detector track circuit containing relay 2DT, under which condition the stick relay 2S is de-energized. The entrance of the west bound train upon the detector track circuit causes the contact 70 of the detector track relay 2DT to assume the de-energized position, and since the stick relay 2S is de-energized, the signal relay OS is de-energized in response to dropping of this contact 70. Dropping of the stick relay OS of course opens the line circuit including the line wire 11¹ by dropping of the contact 71 of the signal relay OS. This in turn, of course, causes the signal lamp I in the tower to be continuously illuminated so long as the detector track relay 2DT is deenergized in response to a west-bound train.

Let us now assume that there is an eastbound train moving over the detector track circuit containing relay 2DT. The entrance of this train upon the detector track circuit causes the stick relay 2S to be picked up and stuck up for reasons described in connection with Fig. 1 of the drawings. Also, this entrance of the train upon the detector track circuit drops the contacts 70 and thereby de-energizes the signal relay OS, bearing in mind that the control relay Z is energized from the tower and that the supplemental circuit for the signal relay presently to be traced is open at the contact 72 of the control relay Z. After a short interval of time the control relay Z will assume its de-energized position in response to dropping of the contact 71 of the signal relay OS, thereby completing an auxiliary circuit for the signal relay OS which may be traced as follows:—beginning at the terminal B of a suitable source of current front contact 73 of the stick relay 2S, wire 74, back contact 72 of the control relay Z, wire 75, back contact 70 of the detector track relay 2DT assuming its deenergized position, wire 76 through the winding of the relay OS to the common return wire C connected to the other terminal of said source. The completion of this circuit will cause the relay OS to pick up which in turn completes the line circuit at the contacts 71 and causes the control relay Z to pick up. As soon as the control relay Z picks up, the auxiliary circuit for the signal relay OS is again opened thereby repeating the cycle of relay operation as just described. In other words, the relays OS and Z will be caused to oscillate, because the de-energizing circuit for the relay OS includes a back contact of the relay Z and this relay Z is controlled by a front contact of the relay OS. This intermittent operation of the

5 relays OS and Z of course causes intermittent interruption of the line circuit 11¹ and in turn causes intermittent de-energization of the line relay LR located in the tower, which in turn causes intermittent illumination of the indicating lamp I, indicating to the dispatcher that there is an eastbound train moving over the detector track circuit for which this indicating lamp I indicates conditions of 10 train movement.

Having thus shown several embodiments of the present invention, and having shown specific circuit arrangements in a system conventionally illustrated, it is desired to be understood that the particular illustrations of the invention selected have been selected for the purpose of disclosing the nature of the invention rather than its scope, and have not been selected with a view of illustrating the 15 exact circuit arrangement preferably employed in practicing the same; and that various changes, modifications and additions may be made to adapt the invention to the particular track, signal and switch lay-out or railway 20 system in connection with which it is to be used all without departing from the scope of the invention or the idea of means underlying the same except as demanded by the scope of the following claims.

30 What I claim is:—

1. In a train indicating system; the combination with a track section located at a point distant to a central office; an indicating lamp in said office for indicating the condition of occupancy of said track section; and means for constantly energizing said lamp if there is a train moving in one direction over

35 said section, causing said indicating lamp to be intermittently lighted when there is a 40 train moving in the opposite direction over said section and causing said lamp to be extinguished when said section is unoccupied.

2. In a train dispatching system, the combination with an outlying track switch, a signal adjacent said switch, a line circuit connecting said signal and a local office energized from said office when said signal shall be permitted to clear, a fouling track circuit associated with said track switch and means for opening said line circuit intermittently when said fouling track circuit is occupied.

3. In a train dispatching system, the combination with an outlying track switch, a signal adjacent said switch, a line circuit connecting said signal and a local office energized from said office when said signal shall be permitted to clear, a fouling track circuit associated with said track switch, and means for opening said line circuit continuously so long as said fouling track circuit is occupied by a train moving in one direction and for intermittently opening said line circuit so long as said fouling track circuit is occupied by a train moving in the opposite 60 direction.

4. In a train dispatching system, the combination with an outlying track switch, two signals associated with said track switch, a polar control relay adjacent said track switch which if energized in one direction permits the clearing of one of said signals and if energized in the reverse direction permits clearing of the other of said signals, a line circuit for controlling said control relay from a local office, a detector track circuit associated with said track switch, and means for continuously opening said line circuit if there is a train moving in one direction over said track circuit and for intermittently opening said line circuit when there is a train moving in the opposite direction over said track switch.

5. In an automatic train control system, the combination with a main track having a passing siding, signals associated with one end of said passing siding, a polar control relay controlled over a line circuit from a distant tower which if energized by current of one polarity permits a main track signal to clear if traffic conditions in advance are safe and is energized by current of the opposite polarity permits a siding signal to clear if traffic conditions in advance are safe, means in the tower for indicating the continuity of said line circuit, and means at the end of said siding for continuously opening said line circuit when a train passes said signals in one direction and for intermittently opening said line circuit if a train moving in the opposite direction passes said signals.

6. In an automatic train control system, the combination with a main track having a passing siding, signals associated with one end of said passing siding, a polar control relay controlled over a line circuit from a distant tower which if energized by current of one polarity permits a main track signal to clear if traffic conditions in advance are safe and if energized by current of the opposite polarity permits a siding signal to clear if traffic conditions in advance are safe, means in the tower for indicating the continuity of said line circuit, a detector track circuit adjacent said signals having a detector track relay, a supplemental relay having a main energizing circuit including a front contact of said detector track relay, a signal relay controlled directly by said supplemental relay and having a front contact included in said line circuit, and an auxiliary circuit for said supplemental relay including a back contact of said signal relay, whereby if the main circuit for said supplemental relay is opened said supplemental relay will be intermittently energized through its auxiliary circuit due to repeated dropping of said signal relay.

7. In an automatic train control system, the combination with a main track having a passing siding, signals associated with one end of said passing siding, a polar control relay controlled over a line circuit from a

distant tower which if energized by current of one polarity permits a main track signal to clear if traffic conditions in advance are safe and if energized by current of the opposite polarity permits a siding signal to clear if traffic conditions in advance are safe, and means in the tower for indicating the continuity of said line circuit, a detector track circuit adjacent said signals having a normally energized detector track relay, a normally energized supplemental relay having a main energizing circuit including a front contact of said detector relay, a normally energized signal relay controlled directly by said supplemental relay having a front contact thereof in said line circuit, a direction relay energized if there is a train moving in one direction but de-energized if there is a train moving in the opposite direction, and an auxiliary circuit for said supplemental relay including a back contact of said signal relay and a contact of said direction relay in series, whereby said line circuit is either opened constantly or intermittently when said detector track relay is de-energized depending on the energized condition of said direction relay.

8. In an automatic train control system, the combination with a main track having a passing siding, signals associated with one end of said passing siding, a polar control relay controlled over a line circuit from a distant tower which if energized by current of one polarity permits a main track signal to clear if traffic conditions in advance are safe and if energized by current of the opposite polarity permits a siding signal to clear if traffic conditions in advance are safe, means in the tower for indicating the continuity of said line circuit, a detector track circuit adjacent said signals having a detector track relay, a supplemental relay having a main energizing circuit including a front contact of said detector track relay, a signal relay controlled directly by said supplemental relay and having a front contact included in said line circuit, and an auxiliary circuit for said supplemental relay including a back contact of said signal relay and control contacts in series, whereby if the main circuit for said supplemental relay is opened and said control contacts are closed said supplemental relay will be intermittently energized through its auxiliary circuit due to repeated dropping of said signal relay and said line circuit will be intermittently broken, but if said control contacts are open when said main circuit is open, said supplemental relay and signal relay will remain de-energized and said line circuit will remain open.

9. In combination, a railway track having a portion thereof isolated from the remaining track, a closed track circuit including the usual track relay and track circuit source of

current, a directional train movement responsive device associated with said track circuit, a line circuit extending from said office to said track portion, an indicating lamp associated with the office end of said line circuit, and means including said track relay and said directional responsive device for continuously illuminating said lamp when said track circuit is occupied by a train moving in one direction and for intermittently illuminating said lamp when said track circuit is occupied by a train moving in the opposite direction.

10. In combination, a local office, a distant track switch of a railway track, signals associated with said track switch, a control relay near said track switch controlled from said office over a line circuit, a circuit for clearing one of said signals in accordance with the condition of energization of said control relay the position of said track switch and traffic conditions ahead of said one signal, an indicating lamp at said office, and means for effecting continuous illumination of said indicating lamp over said line circuit if there is a train passing said one signal in one direction and for effecting intermittent illumination of said indicating lamp if there is a train passing said one signal in the opposite direction.

11. In combination, a local office, a distant track switch of a railway track, signals associated with said track switch, a detector track circuit associated with said track switch, a control relay near said track switch controlled from said office over a line circuit, a circuit for clearing one of said signals in accordance with the condition of energization of said control relay the position of said track switch and traffic conditions ahead of said one signal, an indicating lamp at said office, and means for effecting continuous illumination of said indicating lamp over said line circuit if there is a train moving over said detector track circuit in one direction and for effecting intermittent illumination of said indicating lamp if there is a train moving over said detector track circuit in the opposite direction.

12. In combination with a railway track having two adjacent track portions isolated from each other and from the remaining track, a normally closed track circuit associated with each portion, a direction relay for indicating which of said portions were first occupied thus indicating the direction of movement of a train, a train dispatcher's office, a line circuit connecting said dispatcher's office and said two track portions, an indicating means at the dispatcher's office, and means for intermittently actuating said indicating means during the passage of a train when said direction relay is energized and for continuously actuating said indicating means during the passage of a train when said direction relay is de-energized.

13. In combination with a railway track having two adjacent track portions isolated from each other and from the remaining track, a normally closed track circuit associated with each portion, a direction relay for indicating which of said portions were first occupied thus indicating the direction of movement of a train, a train dispatcher's office, a line circuit connecting said dispatcher's office and said two track portions, means including said line circuit for indicating when said direction relay is energized during the passage of a train over one of said two track portions, a signal associated with one of said track portions, and means for controlling said signal over said line circuit.

14. In combination with a railway track having two adjacent track portions isolated from each other and from the remaining track, a normally closed track circuit associated with each portion, a direction relay for indicating which of said portions were first occupied thus indicating the direction of movement of a train, means for indicating at a distant point the simultaneous occupancy of one of said track portions and the energization of said direction relay, a signal associated with one of said track portions, and means for controlling said signal over said line circuit.

15. In a centralized traffic controlling system, the combination with a section of track of a railway system, a track relay associated with said section, a stick relay associated with said section which stick relay assumes its energized condition when traffic moves in one direction over said section, a local office, a line circuit connecting said office and section, and automatically initiated indicating means for indicating over said line circuit the condition of energization of said track relay and the condition of energization of said stick relay.

16. In a centralized traffic controlling system, the combination with a section of track of a railway system, a track relay associated with said section, a stick relay associated with said section which stick relay assumes its energized condition when traffic moves in one direction over said section, a local office, a line circuit connecting said office and section, and automatically initiated indicating means for distinctively indicating at said office over said line circuit when said stick relay is energized and said track relay is deenergized and when both said stick relay and said track relay are deenergized.

17. In a centralized traffic controlling system, the combination with a section of track of a railway system, a track relay associated with said section, a stick relay associated with said section which stick relay assumes its energized condition when traffic moves in one direction over said section, a local office, a line circuit connecting said office and section, and

indicating means for distinctively indicating at said office and over said line wire the condition of energization of said stick relay for each deenergization of said track relay.

18. In a centralized traffic controlling system, the combination with a section of track of a railway system, a signal associated with said section, a track relay associated with said section, a stick relay associated with said section which stick relay assumes its energized condition when traffic moves in one direction over said section, a local office, a line circuit connecting said office and section, means for controlling said signal over said line circuit, and automatically initiated indicating means for distinctively indicating at said office over said line circuit when said stick relay is energized and said track relay is deenergized and when both said stick relay and said track relay are deenergized.

19. In a centralized traffic controlling system, the combination with a section of track of a railway system, a signal associated with said section, a track relay associated with said section, a stick relay associated with said section which stick relay assumes its energized condition when traffic moves in one direction over said section, a local office, a line circuit connecting said office and section, means for controlling said signal over said line circuit, and indicating means for distinctively indicating at said office and over said line wire the condition of energization of said stick relay for each deenergization of said track relay.

In testimony whereof I affix my signature.
SEDGWICK N. WIGHT.

DISCLAIMER

1,794,565.—*Sedgwick N. Wight, Rochester, N. Y.* TRAIN-DISPATCHING SYSTEM FOR RAILROADS. Patent dated March 3, 1931. Disclaimer filed February 16, 1934, by the assignee, *General Railway Signal Company*.

Hereby enters this disclaimer to claims 13, 14, 15, 16, 17, 18, and 19 of said Letters Patent, which are in the following words, to wit:

“13. In combination with a railway track having two adjacent track portions isolated from each other and from the remaining track, a normally closed track circuit associated with each portion, a direction relay for indicating which of said portions were first occupied thus indicating the direction of movement of a train, a train dispatcher's office, a line circuit connecting said dispatcher's office and said two track portions, means including said line circuit for indicating when said direction relay is energized during the passage of a train over one of said two track portions, a signal associated with one of said track portions, and means for controlling said signal over said line circuit.

“14. In combination, with a railway track having two adjacent track portions isolated from each other and from the remaining track, a normally closed track circuit associated with each portion, a direction relay for indicating which of said portions were first occupied thus indicating the direction of movement of a train, means for indicating at a distant point the simultaneous occupancy of one of said track portions and the energization of said direction relay, a signal associated with one of said track portions, and means for controlling said signal over said line circuit.

“15. In a centralized traffic controlling system, the combination with a section of track of a railway system, a track relay associated with said section, a stick relay associated with said section which stick relay assumes its energized condition when traffic moves in one direction over said section, a local office, a line circuit connecting said office and section, and automatically initiated indicating means for indicating over said line circuit the condition of energization of said track relay and the condition of energization of said stick relay.

“16. In a centralized traffic controlling system, the combination with a section of track of a railway system, a track relay associated with said section, a stick relay associated with said section which stick relay assumes its energized condition when traffic moves in one direction over said section, a local office, a line circuit connecting said office and section, and automatically initiated indicating means for distinctively indicating at said office over said line circuit when said stick relay is energized and said track relay is deenergized and when both said stick relay and said track relay are deenergized.

“17. In a centralized traffic controlling system, the combination with a section of track of a railway system, a track relay associated with said section, a stick relay associated with said section which stick relay assumes its energized condition when traffic moves in one direction over said section, a local office, a line circuit connecting said office and section, and indicating means for distinctively indicating at said office and over said line wire the condition of energization of said stick relay for each deenergization of said track relay.

“18. In a centralized traffic controlling system, the combination with a section of track of a railway system, a signal associated with said section, a track relay associated with said section, a stick relay associated with said section which stick relay assumes its energized condition when traffic moves in one direction over said section, a local office, a line circuit connecting said office and section means for controlling said signal over said line circuit, and automatically initiated indicating means for distinctively indicating at said office over said line circuit when said stick relay is energized and said track relay is deenergized and when both said stick relay and said track relay are deenergized.

“19. In a centralized traffic controlling system, the combination with a section of track of a railway system, a signal associated with said section, a track relay associated with said section, a stick relay associated with said section which stick relay assumes its energized condition when traffic moves in one direction over said section, a local office, a line circuit connecting said office and section, means for controlling said signal over said line circuit, and indicating means for distinctively indicating at said office and over said line wire the condition of energization of said stick relay for each deenergization of said track relay.”
